UNITED STATES PATENT OFFICE.

BEN HILL THOMAS, OF DALLAS, TEXAS.

REFRIGERATING BOX.

Application filed December 15, 1923. Serial No. 680,953.

This invention relates to improvements in refrigerators, the general object of the invention being to so arrange the parts that articles can be taken from the refrigerator 5 or placed therein without exposing the entire interior of the refrigerator to the outside air.

Another object of the invention is to provide the refrigerator with a series of compartments, each of which contains a drawer for holding food and the like, with means for circulating cold air around the compartments.

A still further object of the invention is 15 to provide water holding means in the ice compartment with means for drawing off the water when it is desired to use the same.

This invention also consists in certain other features of construction and in the 20 combination and arrangement of the several parts, to be hereinafter fully described, illustrated in the accompanying drawings and specifically pointed out in the appended claim.

25 In describing my invention in detail, reference will be had to the accompanying drawings wherein like characters denote like or corresponding parts throughout the several views, and in which:—

30 Figure 1 is a front view of the improved refrigerator.

Figure 2 is a side view thereof.

Figure 3 is a section on line 3—3 of Figure 2.

35 Figure 4 is a section on line 4—4 of Figure 1.

Figure 5 is a section on line 5—5 of Figure 3.

40 Figure 6 is a section on line 6—6 of Figure 1.

In these views 1 indicates the body of the refrigerator which is provided with the ice chamber 2 in its upper part and a plurality of drawer receiving compartments 45 3 in its lower part, the drawers being shown at 4. The compartments 3 are spaced apart and are so formed that each compartment is entirely separated from the other compartments so that when a drawer is

50 opened the outside air cannot reach the articles in the drawers in the other compartments. Pipes 5 extend from the ice chamber or compartment into the space 6 between the drawer compartments so that air 55 can circulate and thus keep the drawer compartments at a low temperature. A coil 7

is arranged in the front part of the ice compartment and this coil is provided with a faucet 8 at its outer end which is located outside the refrigerator so that water can 60 be drawn from the coil whenever desired. This coil is adapted to be connected with a source of supply through the valved connections 9 and 9', one connection being arranged at one side of the refrigerator and 65 the other at the rear so that either connection can be used. Tanks 10 are arranged in the ice compartment and these tanks are connected with the coil by the couplings 11 so that they will be filled with water when 70 the supply is turned on. The ice chamber is provided with a drain 12 which may be connected with a hose so that the water from the melting ice can be carried to waste. The coil can also be connected to a tank or 75 the like by means of the connection 13 which contains a valve 14. The ice is introduced into the chamber through the door 15 in the top of the device and it is adapted to rest upon the coil. As shown some of the 80 drawers are arranged in the front of the device and others at the sides so that a number of drawers are provided for containing the articles to be kept cool.

From the foregoing it will be seen that 85 the entire interior of the refrigerator will not be subjected to the warming action of atmospheric air when it is desired to open the refrigerator to remove food therefrom or to place food therein as it is simply 90 necessary to open the drawer which contains the article to be removed or in which it is desired to place an article. Thus a considerable saving in ice is effected. Cold water can also be drawn from the ice chamber 95 at any time by simply opening the faucet and by having tanks a considerable supply of cold water can be kept at hand. The refrigerator is provided with the usual insulated lining which is shown at 16. 100

It is thought from the foregoing description that the advantages and novel features of my invention will be readily apparent.

I desire it to be understood that I may make changes in the construction and in 105 the combination and arrangement of the several parts, provided that such changes fall within the scope of the appended claim.

What I claim is:—

A refrigerator of the class described in- 110 cluding a body having the same divided into upper and lower parts, the upper part con-

stituting an ice chamber, water tanks within said chamber, a coil in the chamber having communication with the tanks, the lower part being divided into individual compartments, drawers movable in said individual compartments said individual compartments being spaced vertically and horizontally to form air chambers, means forming

communication between said air chambers and the ice chamber, means providing for a supply of water to said water tanks and a faucet connected with said coil whereby to withdraw the water from the coil and said tank. 10

In testimony whereof I affix my signature.
BEN H. THOMAS.
